MANUFACTURE OF BOBBIN-SPUN RAYON

Arthur L. Jackson, West Asheville, N. C., assignor
to American Enka Corporation, Enka, N. C., a
corporation of Delaware

Application June 26, 1942, Serial No. 448,655

14 Claims. (Cl. 242—26)

This application constitutes a continuation-in-part of my applications Ser. No. 350,215, filed August 3, 1940, and Ser. No. 397,793, filed June 12, 1941.

The present invention relates to the production of thread packages of synthetic origin, e. g., rayon, and is more particularly directed to an improved method and apparatus for the spinning of such packages according to the bobbin spinning process.

Although bobbin spinning is one of the older systems for the manufacture of rayon, it persists as one of the leading commercial methods. This is unquestionably due to the basic simplicity and versatility of the process, as well as to the superior quality of yarn produced thereby.

Essentially the bobbin spinning process consists in the collection of freshly spun thread upon a foraminated bobbin and the after-treatment of the bobbin-supported wound body. Necessarily, bobbin spinning is intermittent, for a spinning machine must be doffed after the simultaneous preparation of a large number of thread packages; and, since each doffing requires concomitantly the replacement of the filled bobbins by empty ones and the threading up of each unit of the machine, it is inherently advantageous that the winding period, and therefore the weight, of the packages be as great as possible consistent with satisfactory after-treatment. Furthermore, since each bobbin undergoes the same amount of manipulation during after-treatment, it is in the interest of operating economy to treat as large amount of thread as possible on a single bobbin during each such operation.

Previous efforts to attain the foregoing advantages have, in general, followed two lines. One of these involves the use of larger spools and the other is concerned with the winding pattern of the thread.

The employment of large spools has not resulted in a solution of the basic problem of bobbin spinning for, although it is obvious that a bobbin of large size will hold more thread than a small one, there are limits beyond which increases in bobbin size are no longer feasible. These limits are imposed by the structure of various units on which the thread is treated as well as by the structure of twisting machines on which the spinning bobbins are customarily placed upon completion of after-treatment. Then, too, during spinning, mechanical difficulties are encountered if the length of the bobbin is too great, the bobbins being customarily supported from one end only and the thread being laid-up thereon

generally according to a pattern controlled by a reciprocating traverse bar. Thus, the optimum bobbin size is now fairly well stabilized in the rayon industry and recent efforts directed to the production of washable thread packages of increased thickness and weight have been directed to control of the winding operations.

The winding pattern schemes heretofore proposed in the interest of producing heavier and thicker packages of rayon thread susceptible to satisfactory after-treatment have not met with commercial success, although some improvement in the washing qualities of smaller packages has resulted. Usually, pattern control systems involve a cam-directed traverse bar, the purpose of which is to control the manner in which successive layers of thread are laid up on the spinning bobbin. In theory, there have been several patterns suggested which should result in the production of large packages of satisfactory size. In practice, however, this has not been the case, the packages produced being characterized by non-uniform permeability. This non-uniformity may take a number of forms. Thus, thread packages are frequently characterized by areas too dense to be washed at all, while others may be washed, but, because of differences in thickness along various radii of the packages, each after-treatment must be continued for a period of time sufficient to properly wash the portions of greatest radial thickness, with resultant inefficient waste of washing time as regards the portions of lesser thickness. The consequence of these difficulties is, therefore, either thread not uniformly after-treated and hence inferior in quality, or properly after-treated thread more costly to produce than that wound into light-weight packages. Thus, heretofore, the industry has been forced to forego the economy inherent in the preparation of thread packages of substantial size, thickness, and weight.

Another problem which has stood in the way of the preparation of thread packages of increased thickness arises from a mechanical difficulty which has heretofore been encountered. The yarn traverse mechanism which lays up the thread on the spinning bobbin is, of course, subject to reciprocating movement. This movement inherently involves changes in direction and the shock incident thereto. In apparatus known to the prior art, the inertia at the points of changes of direction resulted in overwinds in at least some of the courses of threads. Such overwinds are particularly objectionable in threads of low denier, i. e., below 300. To overcome the diffi-

culty, it has been customary to form thread packages with conical ends so that the slight variations in thread course length will not cause tangling at the ends of the thread package which may result in breakage during unwinding. Naturally, the preparation of packages having conical ends involves a yarn weight loss with respect to a package of similar size, cylindrical in form and having square ends.

It is, therefore, an object of this invention to overcome all of the foregoing difficulties and to provide wound packages of freshly spun thread of synthetic origin having self-supporting square ends and characterized by uniform permeability and density and a thickness and weight greatly in excess of that heretofore attainable.

Another object is the provision of a process and apparatus for the preparation of such packages.

According to this invention, it is contemplated that thread consisting of untwisted filaments be laid up in a cylindrical package form by apparatus so controlled as to accurately produce a desirable pattern and a package of uniform permeability throughout its entire axial length.

It is within the purview of this invention to greatly increase the winding-on periods in the manufacture of bobbin spun rayon while, at the same time, improving the quality of the thread produced.

Other objects and advantages of this invention will be apparent upon consideration of the following detailed description of a preferred embodiment thereof in conjunction with the annexed drawings wherein:

Figure 1 is a view in side elevation of a portion of a bobbin spinning machine incorporating a winding control apparatus constructed according to the present invention;

Figure 2 is a view in section taken along the line 2-2 of Figure 1;

Figure 3 is a view in section taken along the line 3-3 of Figure 2;

Figure 4 is a detail view taken along the line 4-4 of Figure 1;

Figure 5 is a view in section taken along the line 5-5 of Figure 2;

Figure 6 is a view in longitudinal section through a portion of one type of thread package which may be wound according to the present invention;

Figure 7 is a view in longitudinal section of another type of thread package which may be wound according to the present invention;

Figure 8 is a graphic illustration showing how the principle of the tripping coupling is utilized to produce peripheral displacement of the pattern as the thread is laid up on the bobbin; and

Figure 9 is an end elevation of the bobbin diagrammatically showing an end pattern with peripheral displacement whereby the ends are interlocked and overwinds inherently prevented.

The illustrated apparatus consists of a plurality of driven foraminated collecting bobbins 10 onto each of which a freshly spun thread issuing from a spinning bath, not shown, is wound. The thread is laid up on each package by a thread guide 11, these guides being attached to and carried by a traverse bar 12. Traverse bar 12 underlies and reciprocates axially of bobbins 10, the movement thereof being initiated by a cam 13.

It will be seen that each of the bobbins 10 is mounted on a bobbin holder 14 which is provided with a drive shaft 15 mounted in bearings 16 and 17 suitably attached to portions of the

frame 18 of the machine. Each drive shaft 15 is provided with a drive gear 19 meshing with and driven by a gear 20. The gears 20, corresponding in number to the number of bobbins with which the machine is provided, are keyed at spaced points along a shaft 21 mounted for rotation in bearings 22 and 23 supported by portions of frame 18. Shaft 21 constitutes the main drive shaft of the spinning machine, rotation being imparted thereto through gear 24 driven from any suitable source, not shown. It is of course, contemplated that said suitable power source may operate through a variable speed transmission so that the rotational speed of bobbins 10 will be progressively decreased during the winding period to an extent sufficient to compensate for an increased takeup speed brought about by increase in the effective diameter of the bobbin because of the body of thread built thereon. Such variable speed transmissions for maintaining a constant bobbin takeup speed are per se known and form no part of this invention. An example of such an arrangement is shown and described in Patent 2,159,032 to W. G. Lea. It is apparent, therefore, that when shaft 21 is driven each of the bobbins 10 is caused to rotate and, since all gears 19 and 20 are the same size, the speed of rotation of each bobbin 10 will be equal to that of all other bobbins with which the machine is provided.

Upon reference to Figures 1 and 2, it will be noted that, in addition to gears 20 and gear 24, shaft 21 is likewise provided with a gear 25 the purpose of which is to drive cam 13. The movement of cam 13 is effected through a speed reduction gear train consisting of gears 26, 27, 28, 29, 30, and 31. Gears 26 and 27 are keyed adjacent opposite ends of a shaft 32 mounted in bearings 33 and 34. Gear 26 meshes with gear 25 and through shaft 32 drives gear 27. Gears 28 and 29 are mounted on stub shaft 35, gear 28 meshing with gear 27 and gear 29 serving to drive gear 30 of larger diameter. Gear 30 is mounted on a shaft 36 and meshes with gear 31 mounted on hollow hub 37.

The hollow hub 37, in addition to supporting gear 31, likewise supports ratchet 38 which comprises part of an automatic tripping coupling mechanism hereinafter described. Ratchet 38 through pawls 39 drives disc 40 which is keyed to shaft 41. Shaft 41 in addition to supporting disc 40 likewise supports cam 13, the hub 42 of which is keyed thereto for rotation therewith. Inasmuch as shaft 41 must support cam 13 as well as disc 40, bearings 43 and 44 are provided, their design being such as to insure proper absorption of axial as well as radial thrust.

It is now apparent that cam 13, although driven from shaft 21 which drives the bobbins 10, will rotate at a far slower speed than said bobbins. Thus, since the speed of rotation of cam 13 controls the speed of reciprocation of traverse bar 12, while the speed of the bobbins 10 controls the linear speed of take-up, the thread will be wound on said bobbins in the form of a helix, the angle of which depends upon the ratio of cam speed to winding speed. It is equally evident, however, that to insure the production of truly helical wind by the synchronization of the rotation of cam 13 and bobbins 10, the former must develop along a straight line, i. e., the linear movement of its follower must always be directly proportional to the angular displacement of the cam throughout its rotation. In this way, the cam imparts to its follower a reciprocating motion of substantially unvarying characteristics or, in

other words, between reversals of direction at any given time, the follower will move at a constant speed. To this end, cam 13 is provided with a groove, so cut as to insure movement of its follower 45 (Figure 5) in a linear sense in direct proportion to the angular displacement of cam 13 in its rotation with shaft 41. The movement of the follower is transmitted unimpaired to the traverse bar by apparatus to be hereinafter described.

Cam follower 45 is supported in a cross head 46 provided with apertures for the reception of rods 47 and 48 on which the cross head may freely reciprocate while at all times being confined to movement in a single plane. Rods 47 and 48 are rigidly held in spaced sleeves of a pair of brackets 49 and 50 which are attached to vertical portions of frame 18.

Arms 51, see Figure 5, are pivotally attached to cam follower 45 at one of their ends while, at the other end, they are pivotally attached to the free end of a depending arm 52.

Arm 52 is attached, at its end remote from the location of the pivotal connection to arms 51, to a rock shaft 53 mounted in bearings 54 and 55 atop frame 18. Depending from rock shaft 53 are arms 56 and 57 which support traverse bar 12. The support of traverse bar 12 is not direct, however, as may be seen in Figure 2. At the ends of arms 56 and 57 remote from the ends keyed to shaft 53 they are pivotally attached to horizontally extending links 58 and 59 which in turn are pivotally attached at their other ends to depending arms 60, only one of which can be seen in Figure 2. Arms 60 are pivotally attached to a rock shaft 61 and serve to duplicate the movement of arms 56 and 57 on the opposite side of the machine. Thus, in the interest of operating economy the left side of the spinning machine as viewed in Figure 2 may also be provided with a series of bobbins and the laying up of thread thereon can be controlled by cam 13. Because the links 58 and 59 are pivoted to the depending arms 56, 57, and 60, the reciprocating motion ultimately transmitted to thread guide 11 will be in a single moving, substantially horizontal plane thus preventing the guides from tilting in passing from one end to the other on the spools.

Depending from links 58 and 59 are traverse bar supporting members 62 and 63. Thus, when cam 13 is rotated, follower 45 reciprocates causing oscillation of shaft 53 through rocking arm 52. Oscillation of shaft 53, of course, causes reciprocation of traverse bar 12. It should be noted that, although arm 52 is susceptible to simple harmonic motion, the point of pivotal connection of arms 51 thereto is so remote from shaft 53 as to maintain and transmit substantially unimpaired the movement of the cam follower.

It has now been shown that the production of a satisfactory winding control movement of the traverse can be effected by the use of a cam of straight line development. It is further necessary, however, that the thread laid up on the bobbins exactly follow the pattern of movement of the traverse bar to render available the characteristics of cam 13. To this end, a novel type of thread guide has been devised.

Referring again to traverse bar 12, it will be seen that said bar is provided with a plurality of raised portions 64 underlying and in the same vertical plane as the various bobbins 10. A rod 65 is passed through each of the raised portions 64 and a hub 66 is pivoted thereto. Extending upwardly from each hub 66 is a fork 67 the tines of which are adapted to contact tangentially the

respective bobbin. In order to insure firm contact and at the same time to allow for increases in package diameter during winding, a counterweight 68 extends from each hub 66 at a point diametrically opposite fork 67. The distance of the weight from the axis may be made adjustable to insure proper contact consistent with avoidance of injury to threads having different characteristics as regards resistance to abrasion. Because of the fact that the tines of each forked guide 67 actually contact the bobbin and the coils of thread wound thereon, there can be no substantial lag between the movement of the traverse bar and the thread directed thereby. Thus, the thread will follow accurately the pattern of movement of traverse bar 12 even during changes of direction, the break being sharp to insure avoidance of humps at the end of the package.

A plurality of self-threading guides 69, see Figure 4, are attached to traverse bar 12, at spaced points along its length coinciding with the points of location of package contacting thread guides 11. The self-threading guides 69 are provided with a slot at 70 arranged below and in registry with the slot defined by the tines 67 of thread guides 11. Thus, in threading up, the pull between the thread source and the collecting bobbin will cause the thread to slide along the right-hand surface of guide 69, as viewed in Figure 4, thus pulling the thread into the slot at 70. Guide 69 is provided with an extension 71 received in a socket in traverse bar 12, the extension serving to lock the guide in position. A pin 72 constitutes the primary support for guide 69, said pin passing through the traverse bar as can be seen in Figure 2.

By the use of the foregoing apparatus, thicker and heavier packages of thread that are capable of being washed satisfactorily may be produced than was heretofore possible. The packages are characterized by uniform permeability, uniform radial thickness throughout their axial length and by their self-supporting square ends. It is evident that because cam 13 and bobbins 10 are each driven from shaft 21 they are driven in synchronism. The linear movement of the follower associated with cam 13 is directly proportional to the angular displacement of said cam. The consequence of this is the production of truly helical coils throughout the entire winding period. While it is customary to reduce the speed of shaft 21 progressively throughout the winding period so that the peripheral speed of the package will be maintained at a constant value, yet because both the bobbins and the traverse are driven from the same shaft, the synchronism will be maintained. There will be no detrimental relative acceleration or deceleration of the traverse between reversals of movement which will cause localized pattern distortion evidenced in the final package by humps and valleys at each end thereof, the former requiring longer washing periods. The winding path being so accurately controlled allows for very close winding with uniform interstices throughout the package which permit the passage of washing liquid therethrough.

The apparatus thus far described provides packages having straight channels throughout their axial length and are well suited for after-treating certain types of rayon. However, in forming packages of viscose rayon particularly of low denier, objectionable overwinds at the ends of the package may develop. Such overwinds of even the slightest magnitude may cause tangling

or breaking of the threads. Therefore, in these cases, it is contemplated to provide a package having the appearance illustrated in Figure 6 wherein there is shown a cylindrical package containing zigzag channels throughout the axial length of the package. Referring to Figure 9 it will be seen that there is circumferential displacement or angular displacement in a plane normal to the axis of the bobbin of succeeding portions of the pattern, as plotted in Figure 8, which interlocks the ends of the package to prevent objectionable overwinds. Moreover, in this mode of operation, the passage of washing liquid is inhibited to some extent and thus the permeability is still further controlled.

In order to effect circumferential displacement of the pattern or successive portions of the package, an automatic tripping coupling, see Figure 2, is interposed between shaft 41 and main drive shaft 21. The function of this coupling is to periodically, momentarily stop the rotation of shaft 41 and hence cam 13 driven therefrom. The tripping coupling mechanism per se is shown more particularly in Figures 2 and 3, wherein the operation of the ratchet and pawl construction 38 and 39 can be seen. It has been previously stated that disc 40 is keyed to shaft 41 for rotation therewith. Disc 40 is provided with an elongated sleeve-like hub portion 73 which overlies a short portion of shaft 41 extending from the disc in the direction of gear 31. Hub 37 is mounted for rotation about hub 73, as its bearing, hub 37 carrying in addition to gear 31 ratchets 38 and 74 all keyed for rotation therewith. Thus, in order to effect the rotation of shaft 41 in response to rotation of hub 37 carrying driving gear 31 thereon, a mechanism composed of pawls 39 is interposed between ratchet 38 and disc 40. Pawls 39 are pivotally attached to disc 40 at 75 and are urged into engagement with ratchet wheel 38 by springs 76 attached to an arm 77 in turn attached and extending out from disc 40. It will be noted that the pawls 39 are so arranged that only one pawl at a time is engaged by ratchet wheel 38, the remaining pawl being but partially inserted into an adjacent tooth of the ratchet. It is therefore evident that by moving the driving pawl out of engagement with ratchet 38, said ratchet will turn without moving disc 40 until the other pawl 39 abuts the driving edge of the tooth in which it was previously only partially received. During this period, the rotation of shaft 41 will momentarily cease which will cause momentary cessation of the movement of thread guide 11 along bobbin 10.

To effect intermittently the alternate displacement of pawls 39, a star gear 78 is employed, this gear driving through a transmission, a disc 79 on opposite sides of which are mounted pawl displacing pins 80 and 81, each pin acting on its respective pawl. Star gear 78 is mounted on shaft 82 which is attached to disc 40 through a bearing bracket 83. The end of shaft 82 remote from star gear 78 has attached thereto a worm 84. This worm meshes with worm gear 85 mounted on stub shaft 86 anchored in disc 40, said stub shaft also carrying gear 87. Gear 87 meshes with gear 88 mounted on stub shaft 89 and gear 88 likewise meshes with gear 90 mounted on stub shaft 91. The disc 79 carrying pins 80 and 81 is also mounted on shaft 91 and is driven thereby.

The gear train comprising gears 84, 85, 87, 88 and 90 is set in motion by star gear 78. Pin 92 is disposed in the path of the star gear as it turns

bodily with disc 40 and upon striking this pin gear 78 is angularly displaced. After a number of revolutions of shaft 82, dependent upon the gears in the transmission, one of the pins 80 or 81 will displace its pawl 39 thereby causing disc 40 and hence shaft 41 to stop by severance of the driving connection from ratchet 38. Pawl 93 is also attached to disc 40 by pivotal connection to post 94 extending therefrom. This pawl engages ratchet wheel 74 and merely functions to keep shaft 41 and disc 40 from turning ahead of driving ratchet 38.

The tripping coupling described above, when placed in operation, will cause momentary intermittent cessation of movement on the part of

shaft 41. On the other hand, because of the position of the tripping coupling the driving of bobbins 10 will continue uninterrupted. The result, therefore, of momentarily stopping the rotation of shaft 41, and consequently cam 13, is to interrupt the synchronism of the bobbins with the traverse bar 12 driven from cam 13. Inasmuch as a pattern wind is being produced by the driving synchronism, it will be seen that the momentary cessation of movement on the part of the traverse arm will result in circumferential displacement of succeeding portions of the pattern produced with respect to previously wound portions thereof.

In order to provide a package as shown in Figure 7, the automatic tripping coupling mechanism, including the ratchet and pawl connection 38-39, may be entirely eliminated and a direct connection interposed between the main drive shaft 21 and cam drive shaft 41. If, however, the rayon spinning machine has been constructed as fully disclosed herein and it is desired to alter the normal operation thereof in order to provide a package as shown in Figure 7, then the ratchet and pawl connection 38-39 may be maintained throughout the entire winding-on period without eliminating the tripping coupling mechanism per se.

A package having "square-ends" as used throughout the specification and claims means a package in the form of a hollow right cylinder. The "self-supporting" feature with respect to the square ends is self-evident, i. e., the said ends are formed and retained in situ without any outside influence such as thread contacting flanges on the bobbins. The bobbins employed for the present invention may be the normal type insofar as the shape and construction are concerned, although they may vary in size.

The term "pattern" as used herein means the orderly diamond arrangement throughout the cross-wound package and results from maintaining a constant ratio between the speed of the traverse mechanism and the speed of rotation of the bobbins. This synchronous cross-winding causes an orderly arrangement of the diamond formation throughout the body of the package and is, therefore, properly termed the "pattern." When packages are wound by mechanisms involving separate drives for the traverse and the bobbin, no pattern formation is effected as the arrangement of the diamonds is haphazard and occurs in a random manner throughout the body of the package.

Having now described the invention in its preferred form, it is understood that variations and modifications may be made therein without departing from the spirit of the invention, and it is desired that the scope thereof be limited only by the spirit of the appended claims.

What is claimed is:

1. A uniformly permeable freshly spun, cross-wound package of rayon characterized by a plurality of superimposed oppositely directed helical courses of thread, said courses being wound according to a fixed pattern and throughout the body of the package at predetermined points therein, layers of threads circumferentially displaced with respect to layers therebelow, all of the layers constituting the body of the package being of substantially the same axial length to form a cylindrical package having self-supporting square ends and radially zigzag channels.

2. An abnormally heavy and thick, freshly spun, cross-wound package of rayon threads of the order of 300 denier or more, each thread consisting of a plurality of substantially untwisted filaments, said package being further characterized by a plurality of oppositely directed helical courses of thread, said courses being wound onto a bobbin according to a fixed pattern and superimposed on each other except at spaced radial points wherein certain layers are circumferentially displaced with respect to other layers, all of the layers constituting the body of the package being of substantially the same axial length but shorter than the axial length of the bobbin to form a uniformly permeable, cylindrical package having self-supporting, interlocked square ends and radially zigzag channels.

3. A method for the preparation of truly cylindrical packages of freshly spun rayon thread which comprises extruding a freshly spun thread through a coagulating bath and collecting the same on a bobbin at a substantial constant linear speed and guiding it transversely across the surface of the package at a constant speed between reversals of direction at any given time and from a point adjacent thereto, forming a permeable package on the bobbin by superimposing thereon a plurality of oppositely directed helical courses of thread of equal axial length but shorter than the axial length of the bobbin, while maintaining a constant ratio between the rotational speed of the bobbin and rate at which the thread is laid transversely thereof whereby a predetermined fixed pattern is effected throughout the winding period and a package is formed having self-supporting square ends and radial channels throughout the body thereof.

4. A method for the preparation of cylindrical packages of freshly spun rayon thread which comprises collecting a freshly spun thread on a bobbin at a substantially constant linear speed and guiding it transversely across the surface of the package from a point adjacent thereto, forming a permeable package on the bobbin by superimposing a plurality of oppositely directed helical courses of thread of axial equi-length thereon according to a predetermined fixed pattern and, throughout the winding period, circumferentially displacing the pattern at intervals to form a package having self-supporting interlocked square ends and radially zigzag channels.

5. A bobbin spinning apparatus for winding freshly spun thread of synthetic origin into cylindrical packages having square ends which comprises a bobbin, a traverse member, a package contacting thread guide carried by the traverse member and movable axially of the bobbin to direct laying up of the thread thereon, means for reciprocating the traverse member at a constant speed between reversals of direction at any given time and means for driving the bobbin and traverse member in synchronism and for

maintaining the stroke amplitude of the traverse member constant throughout the winding period to produce a pattern wind of constant axial length.

6. An apparatus for winding rayon packages in cylindrical form and having square ends comprising a bobbin, a traverse mechanism including a package contacting thread guide, means for driving said bobbin and said traverse mechanism in synchronism to produce a pattern wind and means for intermittently, circumferentially displacing successively wound portions of the pattern.

10 7. An apparatus for the bobbin spinning of rayon comprising a bobbin, a traverse member, means for continuously producing reciprocating motion of unvarying characteristics, means for driving said means and said bobbin in synchronism to produce a pattern wind, means for circumferentially displacing successively wound portions of the pattern, a connecting means for transmitting substantially unimpaired the said reciprocating motion to the traverse member and a package contacting thread guide carried by said traverse member and movable axially of the bobbin to direct the transverse movement of the thread thereon.

15 8. An apparatus for the bobbin spinning of rayon comprising a bobbin, a traverse member, a cam for continuously producing reciprocating motion of unvarying characteristics, means for driving said cam and said bobbin in synchronism to produce a pattern wind, a connecting means for transmitting substantially unimpaired

20 the motion of said cam to the traverse member to effect a constant stroke amplitude throughout the winding period, and a package contacting thread guide carried by said traverse member and movable axially of the bobbin to direct the transverse movement of the thread thereon.

25 9. An apparatus for the bobbin spinning of rayon comprising a bobbin, a traverse member, a cam for continuously producing reciprocating motion of unvarying characteristics, means for driving said cam and said bobbin in synchronism to produce a pattern wind, a connecting means for transmitting substantially unimpaired

30 the motion of said cam to the traverse member to effect a constant stroke amplitude throughout the winding period, and a package contacting thread guide carried by said traverse member and movable axially of the bobbin to direct the transverse movement of the thread thereon.

35 10. An apparatus for the bobbin spinning of rayon comprising a bobbin, a traverse member, a cam for continuously producing reciprocating motion of unvarying characteristics, means for driving said cam and said bobbin in synchronism to produce a pattern wind, means for intermittently circumferentially displacing successively wound portions of the pattern, a connecting means for transmitting substantially unimpaired

40 the motion of said cam to the traverse member to effect a constant stroke amplitude throughout the winding period, and a package contacting thread guide carried by said traverse member and movable axially of the bobbin to direct the transverse movement of the thread thereon.

45 11. An apparatus for the bobbin spinning of rayon comprising a bobbin, a traverse member, a cam for continuously producing reciprocating motion of a linear speed directly proportional to the angular velocity of the cam, means for driving said cam and said bobbin in synchronism to produce a pattern wind, a connecting means for transmitting substantially unimpaired the motion of said cam to the traverse member to effect

50 a constant stroke amplitude throughout the winding period, and a package contacting thread guide carried by said traverse member and movable axially of the bobbin to direct the transverse movement of the thread thereon.

55 12. An apparatus for the bobbin spinning of rayon comprising a bobbin, a traverse member, a cam for continuously producing reciprocating motion of a linear speed directly proportional to the angular velocity of the cam, means for driving said cam and said bobbin in synchronism to produce a pattern wind, a connecting means for transmitting substantially unimpaired the motion of said cam to the traverse member to effect

60 a constant stroke amplitude throughout the winding period, and a package contacting thread guide carried by said traverse member and movable axially of the bobbin to direct the transverse movement of the thread thereon.

65 13. An apparatus for the bobbin spinning of rayon comprising a bobbin, a traverse member, a cam for continuously producing reciprocating motion of a linear speed directly proportional to the angular velocity of the cam, means for driving said cam and said bobbin in synchronism to produce a pattern wind, a connecting means for transmitting substantially unimpaired the motion of said cam to the traverse member to effect

70 a constant stroke amplitude throughout the winding period, and a package contacting thread guide carried by said traverse member and movable axially of the bobbin to direct the transverse movement of the thread thereon.

75 14. An apparatus for the bobbin spinning of rayon comprising a bobbin, a traverse member, a cam for continuously producing reciprocating motion of a linear speed directly proportional to the angular velocity of the cam, means for driving said cam and said bobbin in synchronism to produce a pattern wind, a connecting means for transmitting substantially unimpaired the motion of said cam to the traverse member to effect

produce a pattern wind, means for intermittently, circumferentially displacing successively wound portions of the pattern, a connecting means for transmitting substantially unimpaired the motion of said cam to the traverse member to effect a constant stroke amplitude throughout the winding period, and a package contacting thread guide carried by said traverse member and movable axially of the bobbin to direct the transverse movement of the thread thereon.

12. An apparatus for the bobbin spinning of freshly spun rayon thread comprising a thread source, a foraminated thread package collecting bobbin and a traverse bar, a cam for continuously producing reciprocating motion of a linear speed directly proportional to the angular velocity of the cam, said cam having a peripheral groove therein, a follower in said groove, means for confining the movement of said follower to a single plane, a rod pivotally connected to said follower, the free end of said rod being pivotally attached to an arm, a rock shaft, said arm being attached to said rock shaft at a point substantially remote from the location of the pivot point, said rock shaft being driven through said arm by the rod connected to the cam follower, a traverse bar driven from the rock shaft to which said arm is attached, a package contacting thread guide carried by said traverse bar, means for driving said cam and bobbin in synchronism, and means intermediate said driving means and said cam for periodically momentarily stopping the movement of the latter.

13. An apparatus for the bobbin spinning of freshly spun rayon thread comprising a thread source, a foraminated thread package collecting bobbin and a traverse bar, a cam for continuously producing reciprocating motion of a linear speed directly proportional to the angular velocity of the cam, said cam having a peripheral

groove therein, a follower in said groove, means for confining the movement of said follower to a single plane, a rod pivotally connected to said follower, the free end of said rod being pivotally attached to an arm, a rock shaft, said arm being attached to said rock shaft at a point substantially remote from the location of the pivot point, said rock shaft being driven through said arm by the rod connected to the cam follower, a traverse bar driven from the rock shaft to which said arm is attached, a package contacting thread guide carried by said traverse bar, means for driving said cam and bobbin in synchronism, and means intermediate said driving means and said cam for periodically momentarily stopping the movement of the latter.

14. An article of manufacture comprising a foraminated bobbin and a freshly spun rayon package tension wound thereon, said package being abnormally thick and heavy and formed of rayon threads of the order of 300 denier or more, each thread consisting of a plurality of substantially parallel, untwisted filaments, the package being characterized by a plurality of superimposed oppositely directed helical courses of thread of equal length cross-wound according to a predetermined fixed pattern, said package being of uniform radial thickness throughout its length and being further characterized by having self-supporting square ends and radial channels throughout the body thereof whereby the package may be after-treated by forcing treating liquid therethrough without physical injury to said filaments and with substantially uniform treatment of the filaments throughout all portions of the package.
